UNITED STATES PATENT OFFICE

JOSEPH M. CRUCET, OF NEW YORK, N. Y., ASSIGNOR TO J. R. PALMENBERG'S SONS, INC.,
OF NEW YORK, N. Y.

DESIGN FOR A LIGHT-CLUSTER SUPPORT

Application filed October 1, 1928. Serial No. 28,347. Term of patent 3½ years.

To all whom it may concern:

Be it known that I, JOSEPH M. CRUCET, a citizen of the United States, residing at New York city, in the county and State of New York, have invented a new, original, and ornamental Design for a Light-Cluster Support, of which the following is a specification, reference being had to the accompanying drawing, forming part thereof.

Figure 1 is a top plan view of a light cluster support according to my design, the lamp socket members being shown by broken

lines to indicate their use in connection with said support.

Figure 2 is a vertical side view of the support, the lamp sockets being omitted to provide a better view of the supporting fixtures.

Figure 3 is a side view of the same to show the relation of the parts forming the design.

I claim:

The ornamental design for a light cluster support as shown and described.

JOSEPH M. CRUCET.
